UNITED STATES PATENT OFFICE.

WILLIAM F. CONKLIN, OF TARENTUM, HOMER S. HOPKINS, OF CRAFTON, AND JOHN M. HOVER, OF PITTSBURGH, PENNSYLVANIA.

SHEET-PILEING MECHANISM.

Application filed March 24, 1925. Serial No. 18,068.

Our invention relates to sheet-piling mechanism, designed particularly for handling metal sheets.

It is one object of our invention to provide a sheet-piling mechanism which receives sheets from a feeding mechanism and automatically stacks them in a pile.

Referring to the accompanying drawings, Fig. 1 is a front elevation of a sheet-metal piling mechanism embodying one form of our invention, parts being in section on the line I—I of Fig. 2; Fig. 2, an elevation of the invention with parts broken away; Fig. 3, a section on the line III—III of Fig. 2, parts being broken away; Fig. 4, a section on the line IV—IV of Fig. 3; Fig. 5, a section on the line V—V of Fig. 4; Fig. 6, a detail section of one side of the table or dropper-frame for the sheets; Fig. 7, a detail section of a portion of said frame; Fig. 8, a view of Fig. 7 rotated toward the observer ninety degrees, portions being omitted and added; Fig. 9, an end view of the table-tripping means, the base therefor being in vertical section; Fig. 10, a diagrammatic view of the electric tripping circuit for the table; and Fig. 11, a diagrammatic view of the table, its support and feeding apron together with a pile of sheets. Fig. 12 is a section on the line XII—XII of Fig. 3.

On the drawings, 1 designates two vertical oppositely disposed columns or posts, shown as I-beams. The anchorage for their lower ends is not shown except conventionally in Fig. 11, but can be readily supplied. Their top ends are connected by the horizontal cross-beam 2.

The frame 2^a of our mechanism has vertical travel between the columns and is guided on the columns by the rollers or wheels 3 carried by the outer faces of the side members 4 and 5 of the frame, some of the rollers running on the front edge of the columns and some on the rear edge 45 thereof. The rear ends of the members 4 and 5 are connected together by the hollow box-like cross-member 6, in which the horizontal right and left screw 7 is mounted. The screw is rotated by the crank 8 or other 50 means. The front ends of the frame have their side members 4 and 5 connected by the T-bar 9 and the platform 10 above the T-bar. The side members 4 and 5 are provided at their upper and lower edges with the wide 55 inturned flanges or guards 11 and 12, spaced

apart wider than the width of the sheets to be piled.

The platform 10 is suspended from the cross beam 2 by two ropes 13 which pass down and under the sheaves 14 secured to the platform, and under and up from the sheaves 15, also secured to the platform. From the sheaves 15 the ropes go to the hoisting device represented conventionally by the numeral 16.

17 is a motor mounted on the platform 10 and drives through the reduction gear housing 18, the shaft 19 having bearings in the posts 20 standing on the platform 10. The shaft 19 carries the pinion 21 which 70 meshes with the spur-gear 22 on the shaft 23 having bearings in the post 24 and the right hand post 20.

The shaft 19 carries the sprocket pinion or wheel 25 over which the sprocket chain 75 26 runs, the lower end of the chain running on the sprocket pinion or wheel 27 on one of the trunnions 28 supported in the hangers 35 suspended from the platform 10. The trunnions 28 carry the upper sheet-feeding 80 roll 29, the lower roll 30 cooperating therewith being supported in the blocks 31 attached to the hollow cross-bar 32, in which rotates the shaft 33 having the crank-arms 34 at its ends beyond the side members 4 and 5. 85

The shaft 23 carries beyond the side member 4 the sprocket-wheel 36 which carries the sprocket-chain 37 running on the sprocket-wheel 38 on the shaft 33.

The shaft 19 carries the sprocket-wheel 90 39 which carries the sprocket-chain 40 running on the sprocket-wheel 41 which turns loosely on the bar 32. The sprocket-wheel 41 carries rigidly therewith the sprocket-wheel 42 which drives the sprocket-chain 43 95 running on the sprocket wheel 44 on the conveyor shaft 45. The shaft 45 is supported by the side bars 46 of the conveyor which bars are pivotally attached by the bars 47 to the cross-bar 32. The shaft 45 100 has the two pulleys 48 on which the conveyor belts 49 run, the front ends of the belts running on the suitable front sheaves not necessary to be shown. The skid or guide bar 50 is supported by the bar 32 and the shaft 45 between the pulleys 48 to prevent a sheet from going below the roll 30.

At the rear of the rolls 29 and 30 is the sheet-receiving and dropping table or mechanism which includes the two oscillatory 110

shafts 51 and 52, having their rear ends mounted in the nuts or blocks 53 and 54, respectively. The front ends of the shafts 51 and 52 are mounted respectively in the 5 hangers 55 and 56 suspended by and slideable along the T-bar 9. 57 is a right and left threaded shaft working in the hangers as nuts, and mounted in the side members 4 and 5. One end of the shaft 57 has the 10 bevel gear 58 which meshes with the bevel gear 59 on the shaft 60 having therein the universal joint 61, as the front end of the shaft is at a higher level than the rear end thereof. The rear end of the shaft is connected to the shaft 7 by the bevel gears 62. The shafts 7 and 57 are so threaded that when the crank or handle 8 is turned, the shafts 51 and 52 are caused to approach each other or to recede from each other to 15 accommodate the different widths of the sheets to be received on the rollers.

The shafts 51 and 52 have attached to their sides vertical plates 63 through which pivot bolts 64 extend, the bolts serving as 20 bearings for the horizontal dropper rollers 65. The rows of rollers 65 projecting toward each other from the shafts 51 and 52 are each provided with a bar or guide 66 held in place at the free ends of the rollers 25 by the said bolts 64. The guides 66 prevent the advancing ends of the sheets from going beneath any of the rollers 65.

In front of the rolls 29 and 30 and below the roll 29 is an angle bar 76 extending 30 transversely across the machine and having the ends of its horizontal member 67 extending through slots 68 in the side members 4 and 5 and the blocks 69 attached to the outer faces thereof. The said ends of 35 the member 67 are pivotally connected to the cranks 34 by the pitmen 70 by the pivots 71 and 72.

The angle bar 76 has the upwardly extending member 73 between the side members 4 and 5, the member 73 being cut away at 74 to allow the angle bar to pass beneath the roll 30. The member has at each end a horizontal slot 75.

Near the ends of the roll 30 we provide 40 two tripping attachments or frames 78 for controlling the oscillation of the shafts 51 and 52. We will describe one only as they are alike. On the rear face of the member 73 we mount on the pivot 77 the tripper frame 78 having the front member 79 extending upwardly and rearwardly and terminating near the line of the pass of the rolls 29 and 30. Near the upper end of the member 79 there is mounted the roller 80 45 in line with a metal sheet moving toward the roll pass. From the upper end of the member 79 there is a downwardly projecting sheet-pusher member 81 having the toe 82 adapted to engage the under side of the 50 member 67 and prevent the spring 83 from

lifting the tripping attachment beyond the position shown in Figs. 1 and 9.

One end of the tripping frame has the movable switch member 84 normally held by the oppositely-acting springs 85 out of 70 engagement with the electric contact 86. The member 79 has the finger 87 adapted to engage and pass the switch member 84 when the member 79 is depressed. When the tripping frame moves upwardly the toe 75 first engages the switch member 84 and moves it into engagement with the contact 86 and then passes the switch member and assumes the position shown in Fig. 9. To the switch member 84 and the contact 86 are 80 connected the wires 88 and 89 in series with the battery 90 and the winding 91 of the electromagnet 91'. The magnet when energized operates the clutch operating lever 92 which operates the clutch marked 93 to connect the shaft 23 to the gear 22. This clutch may be any type which is adapted to open 85 after the gear 22 turns a complete revolution.

A sheet 94 coming from the conveyor 90 belts 49 engages the rollers 80, depresses the frames 78, and enters the pass of the rolls 29 and 30 which feed the sheet 94 to the upper side of the dropper table, that is, upon the rollers 65. As soon as the sheet has 95 passed the rollers 80, the tripping frame is pushed up by the spring 83 and causes the tripping circuit to be closed, as already described. The clutch is thrown in by the lever 92 and the shafts 23 and 33 make one 100 complete revolution and stop, the sprocket wheels 36 and 38 being of the same size. The rotation of the shaft 33 causes the pitmen 70 to push the angle bar 76 one stroke rearwardly and one stroke forwardly, the 105 ends of the angle bar member 67 riding in the slots 68. When the bar 76 moves backwardly, the member 81 of the tripper frame 78 engages the end of the sheet 94 and shoves it to a definite position on the dropper table. 110

When the bar 76 moves rearwardly it pushes rearwardly the two bars 95 and 96 having a jaw 97 fitting over the top edge of the member 73 of the angle bar. The bars 5 and 96 extend through the hangers 55 115 and 56, and they each bear beyond the hangers two vertical rollers 98. Between the pairs of rollers are the horizontal guide bars 99 and 100, pivoted at front ends to the horizontal angle plates 101 and 102, 120 which are pivoted at their rear ends to the blocks 53 and 54 by the ears 103 thereon, the pivot 104 for one of the plates being shown in Figs. 7 and 8. The bars 99 and 100 have their middle portions inclined right 125 and left respectively, as shown in Fig. 3, their rear or free ends being normally seated against the stops 105 on the outer edges of the plates 101 and 102, there being springs 106 between the bars and the stops 107 on 130

the inner edges of the plates. The springs are stiff enough to resist compression and cause the plates 101 and 102 to move inwardly or toward each other, when the bars 5 95 and 96 move rearwardly. The plates have the vertical flanges or members 108 which engage the lateral edge of the metal sheets and accurately center them as they are pushed to their final position on the 10 dropper table rollers 65. The flanges 108 have the depending portions 112 to guide the sheets as they are dropped from the rollers 65 to the pile 109. In case a sheet is of extra 15 width and prevents the full inward movement of the plates 101 and 102, the bars 95 and 96 will push the bars 99 and 100 inwardly, the springs 106 yielding and thereby preventing damage to the parts.

The forward end of the bars 51 and 52 are 20 provided with cam-plates 110 and 111, having their horizontal front ends in the slots 75 in the bar 76. The portions of the cam-plates attached to the bars 51 and 52 are 25 vertical, the cam-plates being given a long quarter turn or twist between their ends, the turns being such as to allow the slots 75 to rotate the cam plates ninety degrees as the angle bar 76 moves from one extreme 30 position to the other. The front ends of the cam-plates are horizontal for a sufficient distance to allow the pusher member 81 to move the sheets for some distance before the twists in the cam plates cause the bars 51 and 52 to swing the rollers 65 down- 35 wardly. The parts are so proportioned and timed that the sheets are dropped when the pusher member 81 reaches a definite place so that the front end of the pile 109 shall be squared and vertical.

40 In Fig. 11 we show a diagram to illustrate the fact that the frame 2^a can be raised to various levels as the pile 109 of sheets grows. The conveyor indicated by the side bars 46 thereof may be swung on its front 45 end so as to take any position between the dotted and full line positions shown. The frame 2^a when lowered completely, as shown in full lines, allows access to the pile 109 for applying thereto suitable hoisting 50 devices. When the frame 2^a is to be lowered below the top of the pile 109, the crank must first be turned to cause the dropper table members to move laterally between the flanges or guards 11 and 112, and 12 and 113, 55 so that the rollers and associated devices will not be accidentally damaged and so that the rollers will be withdrawn past the sides of the pile 109.

We claim—

60 1. In a sheet-metal piling machine, means for supporting sheets above a position where they are to be piled, one upon another, means for feeding sheets to said position, means for moving the supporting means from beneath the sheets and beyond the sides of the pile of

sheets and for then lowering the supporting means at the sides of the pile.

2. In a sheet-metal piling machine, means for supporting sheets above a position where they are to be piled, one upon another, means 70 for feeding sheets to said position, means for moving the supporting means from beneath the sheets and beyond the sides of the pile of sheets and for then lowering the supporting means to the bottom of the pile. 75

3. In a sheet-metal piling machine, a frame, means supported by the frame and temporarily supporting sheets directly above a position where they are to be piled, one upon another, means for moving the supporting means from beneath the sheets, means for raising and lowering the frame, and means for moving the supporting means laterally on the frame beyond the sides of a pile of sheets deposited by the supporting 80 means, whereby the frame with said supporting means may be lowered opposite the edges of the piled sheets.

4. In a sheet-metal piling machine, means temporarily supporting sheets directly above 90 a position where they are to be piled, one upon another, means for moving the supporting means from beneath the sheets, means for raising and lowering the supporting means, and means for moving the supporting means laterally beyond the sides of a pile of sheets deposited by the supporting means, whereby the said supporting means may be lowered to permit access to the sides 95 of the pile for applying hoisting devices and other purposes, in combination with a shield protecting the said supporting means when the latter have been moved laterally. 100

5. In a sheet-metal piling machine, a frame, a pair of spaced oscillatory shafts, devices 105 carried by the shafts and arranged to receive sheets fed thereupon, two spiral plates, means movable longitudinally of the plates and causing them to rotate the shafts simultaneously to release the sheets from said 110 devices.

6. In a sheet-metal piling machine, a frame, a pair of spaced oscillatory shafts, devices carried by the shafts and arranged to receive sheets fed thereupon, spiral means oscillatory with the shafts, means movable longitudinally of the spiral means and causing the turning of the shafts simultaneously to release the sheets from said devices. 115

7. In a sheet-metal piling machine, a pair of horizontal shafts, opposing devices carried by the shafts and arranged to support the opposite sides of sheets fed thereupon, means preventing the leading ends of the sheets from passing beneath any of said devices, and means for simultaneously rotating the shafts to release the sheets from the said devices. 120

8. In a sheet-metal piling machine, a pair 130 of horizontal shafts, opposing devices car-

- ried by the shafts and arranged to support the opposite sides of sheets fed thereupon, means preventing the leading ends of the sheets from passing beneath any of said devices, and means for simultaneously rotating the shafts to release the sheets from the said devices, the said devices bearing rollers on which the sheets ride.
9. In a sheet-metal piling machine, a table upon which sheets are fed and from which they are dropped to form a pile beneath, and means for centering the sheets laterally before they are dropped and while they are on the table.
10. In a sheet-metal piling machine, a pair of horizontal shafts, means carried by the shafts for receiving and supporting the opposite sides of sheets fed thereupon, means for simultaneously moving the shafts toward each other and away from each other to accommodate sheets of different widths, and means adjustable with the shafts and movable laterally to center the sheets on the table.
11. In a sheet-metal piling machine, a pair of horizontal shafts, means carried by the shafts for receiving and supporting the opposite sides of sheets fed thereupon, means for simultaneously moving the shafts toward each other and away from each other to accommodate sheets of different widths, and means adjustable with the shafts and movable laterally to center the sheets on the table, said last means comprising a pair of bars pivoted at their rear ends and having depending flanges to engage the side edges of the sheet.
12. In a sheet-metal piling machine, a pair of horizontal shafts, means carried by the shafts for receiving and supporting the opposite sides of sheets fed thereupon, means for simultaneously moving the shafts toward each other and away from each other to accommodate sheets of different widths, and means adjustable with the shafts and movable laterally to center the sheets on the table, said last means comprising a pair of bars pivoted at their rear ends and having depending flanges to engage the side edges of the sheet and also having depending guides to direct the sheets downwardly when dropped from the said receiving and supporting means.
13. In a sheet-metal piling machine, a table upon which sheets are fed preparatory to dropping them to form a pile beneath, means movable laterally at each side of the sheets to center them on the table, and means for moving the first means toward each other, the said last means including a yielding connection, effective when an extra wide sheet is engaged by the first means.
14. In a sheet-metal piling machine, a table to receive sheets fed thereupon, laterally movable plates arranged at opposite edges of the sheet and having depending flanges for engaging the sheets and centering them on the table, cam plates pivoted at one end to the first named plates, and springs connecting the remaining ends of the cam plates to the other plates, said springs being stiff enough to cause both plates to move together normally, but weak enough to yield when the said flanges engage the edges of an extra wide sheet.
15. In a sheet-metal piling machine, a pair of sheet-feeding rolls, a table at the rear of the rolls to receive the sheets, means for discharging the sheets from the table, means displaced by a sheet as it enters the roll pass and released as the sheet passes beyond said means, and means set in operation upon the return of the displaced means, for setting the discharging means in operation.
16. In a sheet-metal piling machine, a pair of sheet-feeding rolls, a table at the rear of the rolls to receive the sheets, sheet-pushing means depressed by a sheet entering the roll pass and released at about the time the sheet leaves the roll pass, and means for moving the said first means rearwardly to push the sheet to a definite position.
17. In a sheet-metal piling machine, means for temporarily supporting the opposite edges of horizontal sheets and then releasing them to form a pile, and means for first moving the supporting means laterally beyond the sides of the pile and then downwardly, and a shield to receive the supporting means when so moved laterally.
18. In a sheet-metal piling machine, a table for temporarily supporting sheets and then releasing them to form a pile beneath the table, means for raising the table to keep the latter a selected distance above the top of the pile, and means feeding sheets to the table and having vertical travel with the vertical travel of the table.
19. In a sheet-metal piling machine, a pair of sheet-feeding rolls, a table at the rear of the rolls to receive the sheets, means for pushing the sheets to a definite position beyond the pass of the rolls, and means controlling the operation of the pushing means and restrained by the sheets in the roll pass and released from the sheets at about the time they leave the roll pass.

In testimony whereof we hereunto affix our signatures this 18th day of March, 1925.

WM. F. CONKLIN.
HOMER S. HOPKINS.
JOHN M. HOVER.
